Attest

United States Patent Office.

FRANCIS A. MACK, OF NILES, MICHIGAN.

Letters Patent No. 91,648, dated June 22, 1869.

IMPROVEMENT IN DOUBLE-ACTING PUMPS.

The Schedule referred to in these Letters Patent and making part of the same.

To all whom it may concern:

Be it known that I, FRANCIS A. MACK, of Niles, in the county of Berrien, and State of Michigan, have invented certain new and useful Improvements in the Construction of Double-Acting Pumps; and I do hereby declare that the following is a full and exact description thereof, reference being had to the accompanying drawings, making a part of this specification, in which—

Figure 1 is an elevation, with one side in section.

Figure 2, a plan.

Like letters of reference indicate corresponding parts in all the figures.

This pump is of that class known as double-acting, in which two cylinders and pistons, with water-ways, connected with a single induction and eduction-passage are employed.

The invention does not consist in any new features in the working-parts, but rather in the special construction, in which wooden bodies are employed with the metallic cylinders, and other parts bolted and clamped thereto; the object being to secure great cheapness and strength, and to supply such a pump for various places and purposes.

In the drawings—

A A' represent the cylinders, which are made of metal, with both ends open.

These cylinders are simply clamped between the two wooden bodies B and C by screw-bolts, a a a a, having packing to make them tight.

The nuts on lower end of bolts a also clamp in place on the under side of C, a metallic water-passage, D, with induction-tube b, extending down a suitable distance below.

This water-passage conducts the water to openings c c, made through C, into the cylinders A A'.

This water-passage D may be dispensed with in wells already dug.

A metallic water-chamber, E, is also bolted on top of B, from which extends eduction-tube d to the top of the well.

A valve, j, is situated over opening i.

The body B consists simply of three or more layers, f f f, of wood, the exterior ones of which are entire or unbroken, while the inner one or ones have a large opening, g, cut out of the centre, communicating at h with the cylinders, and at i with the chamber E.

The arrangement of the pistons G G, piston-rods k k, cross-bar H, and operating-lever I, and stuffing-boxes J J, is similar to those now in use.

The platform K is connected with C by straps l l, the object being to properly support the pump below water at a suitable distance from the bottom, and prevent mud and sediment from drawing into the pump.

This I believe to be a new feature, and forms an important part of the construction.

I disclaim any of the operating-parts of the pump.

The novelty in my case consists simply in the construction, consisting of the wooden bodies B C K, with the metallic parts A, A, D, and E, bolted and clamped thereto in such a manner as to constitute a solid whole, thereby forming a pump of combined wood and iron, of exceeding cheapness and strength, and not liable to get out of order, and can be used in a common well, or be attached to a tube-well.

What I claim as my invention, and desire to secure by Letters Patent, is—

1. The body B, consisting of a series of wooden layers, f, and provided with an internal space, g, the metallic chambers D E, wooden platform C, and metallic cylinders A A', combined together in the manner and for the purpose described.

2. The sub-platform K, between which and the platform C, is a free space, as arranged in relation to the other parts of the described pump, substantially as and for the purpose described.

In witness whereof, I have hereunto signed my name, in the presence of two subscribing witnesses.

F. A. MACK.
